UNITED STATES PATENT OFFICE.

JOHN HAYS HAMMOND, JR., OF GLOUCESTER, MASSACHUSETTS.

RADIODYNAMIC TORCH LAUNCHING MECHANISM.

1,418,870.

Specification of Letters Patent. Patented June 6, 1922.

Application filed August 14, 1913, Serial No. 784,690. Renewed January 30, 1919; Serial No. 274,128.

To all whom it may concern:

Be it known that I, JOHN HAYS HAMMOND, Jr., a citizen of the United States, and a resident of Gloucester, in the county of Essex and State of Massachusetts, have invented an Improvement in Radiodynamic Torch-Launching Mechanism, of which the following description, in connection with the accompanying drawings, is a specification, like characters on the drawings representing like parts.

This invention relates to mechanism for releasing or discharging objects from their support, and more especially for releasing them from a moving body, and in particular it relates to radio-dynamic mechanism for launching torches from a moving vessel.

In order that the principle of the invention may readily be understood I have disclosed a single embodiment thereof in the accompanying drawing, wherein

Fig. 1 is a view partially in longitudinal section and partially diagrammatic, of one form of mechanism for practising my invention; and

Fig. 2 is a side elevation, somewhat diagrammatic in character, representing a series of torches supported upon a moving vessel in position for discharge.

In prior applications for U. S. Letters Patent I have disclosed means for controlling moving bodies at a distance by radiant energy. While my invention is not restricted thereto, I contemplate, in accordance with the present invention, the control of a torpedo or other vessel by radiant energy from a distance and I equip the said vessel with objects to be released or discharged therefrom by impulses transmitted from the distant control station. While these objects may be of any suitable type or character, they are preferably torches or illuminating devices which are intended to be discharged into the water at night when the vessel has approached the vicinity of the enemy, so that the person at the distant control station may be enabled to see the vessel which he is controlling and to guide the movements thereof with more certainty.

It is apparent that my invention is not limited to the discharge of torches but may be employed for discharging other objects such as bombs and that the moving body carrying said objects may be a vessel propelled through the water or a vehicle upon

land or in the air such for example as an aeroplane.

Referring to the drawing wherein I have shown a single embodiment of means for carrying out my invention, I have indicated the open, oscillatory receiving circuit at 1, this being connected to the winding 2 of a closed, oscillatory circuit of any suitable type and shown as having therein a condenser 3 and a suitable detector 4 for electrical oscillations. At 5 I have indicated a sensitive relay or other contact making device. These parts may be of any suitable construction not herein necessary more fully to describe or indicate.

In accordance with my invention, I provide suitable means operated through the instrumentality of the closed receiving circuit for releasing or discharging objects and in the disclosed embodiment of my invention, for launching torches from a moving vessel. While any suitable means may be employed for the purpose, I preferably employ compressed fluid means under the control of said receiving circuit and operatively connected to the torch-launching mechanism.

For that purpose, I have herein indicated at 6 a suitable battery or other source of electrical energy in the relay circuit and at 7 I have diagrammatically represented a solenoid magnet, the plunger 8 whereof is operatively connected to or has formed therewith, or attached thereto, a valve 9 mounted in a suitable casing and having a port 10 adapted to be placed in register either with the intake 11 leading from a suitable source of compressed fluid such for example as a reservoir of compressed air, or with an exhaust 12 leading to any suitable point of discharge. When an impulse is transmitted from the distant sending or control station and is received by the oscillatory circuit 1, the solenoid magnet 7 is energized and the valve 9 is thereby moved to place its port 10 in register with the intake 11. Upon the termination of the said impulse the valve is returned to the position shown in Fig. 1 by the spring 13, thereby placing the port 10 in register with the exhaust 12.

The intake and exhaust passages 11 and 12 communicate with a cylinder 14 at the same side of the piston 15 thereof so that upon admission of motive fluid into the cylinder the piston is moved toward the right viewing Fig. 1, and when the exhaust passage 12 is

opened the piston is permitted to move toward the left.

I have herein represented the piston 15 as having a plunger 16 provided with an enlarged end or head 16' adapted to engage a lever 17 pivoted at 18 upon any suitable support and normally held in the position shown by suitable means such as the coiled spring 19, the construction being such that 5 upon the outward movement of the plunger 16, its head 16' swings the upper end of the lever 17 to the right until the lever is permitted, upon the movement past it of the head 16', to snap back toward the left under 10 the tension of the spring 19.

Upon any suitable support, I mount a valve casing 20 having therein a valve 21 provided with an inlet port 22 and with an exhaust 23 adapted alternately to be brought 20 into register with an intake passage 24 leading from any suitable supply of compressed motive fluid such as air and with an exhaust passage 25 leading to any suitable point of discharge. The valve 21 is normally held 25 by compressed spring 26 with its port 23 in register with the exhaust passage 25 and with the passage 27 having branches 28, 29. The said valve 21 is provided with a plunger or extension 30 connected to or extending 30 into the path of movement of the lever 17 so that upon the admission of motive fluid through the passage 11 into the cylinder 14 and the movement of the piston 15 and its plunger 16 toward the right, 35 viewing Fig. 1, the valve 21 and its plunger 30 are moved toward the left, thereby bringing the port 22 of said valve 21 into register with the intake passage 24 and the passage 27.

40 I have diagrammatically indicated the hull of the vessel, which may be a torpedo, at 31. Thereon at any suitable point I provide a discharge-runway or chute 32 which I have herein represented as inclined but 45 which may be upright or otherwise positioned so as to permit the discharge of objects therefrom. Preferably I effect the discharge of these objects through the action of gravity and I have herein represented a 50 series of torches 33 as positioned in the runway between the upper and lower walls thereof. These torches or illuminating objects may be of any suitable character but preferably they are acetylene torches constructed automatically to ignite upon contact with the water.

In order normally to hold the torches in the runway or chute, I may provide any suitable mechanism but herein for the purpose 60 I have represented a pair of plungers 34 carried by pistons 35 mounted in cylinders 36 suitably supported in alinement upon the vessel and provided with coil springs 37 which normally hold the plungers in the position indicated in Fig. 1 and prevent the

discharge or release of the torches from the runway or chute. The pipes or passages 28, 29 communicate at 38—38 with the forward ends of the cylinders 36 so that upon admission of compressed motive fluid into the passages 28, 29, the pistons 35 and their plungers 34 are forced outwardly, compressing the springs 37, and permitting the release of the leading one of the series of torches.

When an impulse is received by the oscillatory circuit 1 and the solenoid magnet 7 is energized, the plungers 34—34 are momentarily withdrawn and allow the leading torch only to drop overboard into the water. Before the next torch reaches the point of 75 discharge the plungers 34—34 are returned to their holding position by the action of the springs 37—37. The compressed motive fluid is admitted to the cylinder 36 with a sudden impulse, and before the second torch 80 has arrived at the mouth of the runway or chute, the inflow of the motive fluid is cut off and the exhaust port is opened by the sudden return movement of the lever 17, allowing the motive fluid to escape into the 85 atmosphere and the springs 37—37 to re-expand, thereby preventing the discharge of the second torch, which now becomes the leading torch of the series, and may be discharged by another impulse from the distant control station. The cylinders 14 and 36 are preferably provided with small ports 90 39 to prevent compression of the contained air.

Having thus described one illustrative embodiment of my invention, I desire it to be understood that although specific terms are employed, they are used in a generic and descriptive sense and not for purposes of limitation, the scope of the invention being set 100 forth in the following claims:

1. In combination, torch supporting mechanism, compressed fluid means for releasing the torches, and means responsive to radiant energy from a distance for operating said 105 compressed fluid means.

2. A moving body having a support for objects to be discharged, compressed fluid means for releasing said objects, and means responsive to radiant energy from a distance 110 for rendering operative said compressed fluid means.

3. A vessel having a support for objects to be discharged, compressed fluid means adapted to permit the successive release of 115 said objects, and means responsive to radiant energy from a distance to render operative said compressed fluid means.

4. A vessel having a support for objects to be discharged, a pair of plungers to hold the objects upon the support, compressed fluid means for operating said plungers, and means responsive to radiant energy from a 120 distance for rendering operative said compressed fluid means.

5. A vessel having an inclined discharge-runway, means to support objects thereon, and means responsive to radiant energy from a distance to release said objects from 5 said supporting means.

6. A vessel having a support from which objects may be discharged by gravity, and means responsive to radiant energy from a distance for releasing said objects from 10 said support.

7. A vessel having a torch-receiving chute, and means responsive to radiant energy from a distance for releasing said torches from said chute.

15 8. A vessel having a torch support, a plunger to maintain said torch upon said support, compressed fluid means for operating said plunger, a valve controlling the operation of said compressed fluid means, and 20 means responsive to radiant energy from a distance for operating said valve.

9. A vessel having thereon a closed receiving circuit responsive to radiant energy from a distance, a solenoid operated by the said 25 circuit, a valve operated by the solenoid, a compressed fluid receiving cylinder having a fluid admission port controlled by said valve, a torch support, plungers to maintain torches upon said support, compressed fluid 30 means for operating said plungers, and means controlled by the fluid in said cylinder for effecting the operation of said compressed fluid means.

10. A vessel having thereon a closed receiving circuit responsive to radiant energy from a distance, a solenoid operated by said circuit, a valve operated by the solenoid, a compressed fluid receiving cylinder having a fluid admission port and a fluid discharge 40 port controlled by said valve, a torch support, plungers to maintain torches upon said support, compressed fluid means for moving said plungers, and means controlled by the fluid in said cylinder for effecting the operation of said compressed fluid means.

11. Means for releasing bodies at a distance by radiant energy comprising a closed receiving circuit, a solenoid adapted to be operated thereby, and a valve connected to 50 said solenoid and controlling the admission and exhaust of compressed motive fluid, and means under the control of said valve for releasing said bodies.

12. The combination with means for holding a plurality of objects and for guiding said objects to move in a predetermined path of retaining means normally projecting into the said path for preventing said objects from moving in said path, and means re-

sponsive to a continuous impulse of energy 60 to cause said retaining means to move out of said path to permit one of said objects to be discharged from said supporting means and then while said impulse continues to cause said retaining means to return into said path to retain the succeeding objects in 65 said supporting means.

13. The combination with inclined supporting means for holding a plurality of objects and for guiding said objects to move 70 in a predetermined path of retaining means normally projecting into the said path for preventing said objects from moving in said path, and means responsive to a continuous impulse of energy to cause said retaining 75 means to move out of said path to permit one of said objects to be discharged from said supporting means and then while said impulse continues to cause said retaining means to return into said path to retain the 80 succeeding objects in said supporting means.

14. The combination with inclined supporting means for holding a plurality of objects and for guiding said objects to move 85 in a predetermined path of oppositely disposed reciprocating plungers normally projecting into said path to prevent the release of said objects from said supporting means, and means responsive to a continuous impulse of energy to cause said plungers to 90 move simultaneously out of said path to permit one of said objects to be released from said supporting means, and then while said impulse continues to cause said plungers to return into said path to retain the 95 succeeding objects in said supporting means.

15. The combination with an inclined chute for holding a plurality of movable objects, and for guiding said objects to move in a predetermined path of a pair of oppositely disposed aligned plungers normally projecting into said path to prevent said objects from moving in said path, and fluid pressure means responsive to a continuous impulse of energy to cause said plungers to 100 move simultaneously out of said path to permit one of said objects to be discharged from said chute, and then to cause said plungers to return into said path to retain the 105 succeeding objects in said chute. 110

In testimony whereof, I have signed my name to this specification in the presence of two subscribing witnesses.
